UNITED STATES PATENT OFFICE

133,997

DESIGN FOR A BANK

Bruce A. Mackey, Libertyville, Ill.

Application March 25, 1942, Serial No. 106,316

Term of patent 3½ years

To all whom it may concern:

Be it known that I, Bruce A. Mackey, a citizen of the United States, residing at Libertyville, in the county of Lake and State of Illinois, have invented a new, original, and ornamental Design for a Bank, of which the following is a specification, reference being had to the accompanying drawing, forming a part thereof.

In the drawing:

Fig. 1 is a side elevational view of a bank showing my new design; and Fig. 2 is a plan view thereof.

I claim:

The ornamental design for a bank, as shown.

BRUCE A. MACKEY.
